(57) CLAIM

The ornamental design for a test kit, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a test kit, including a flap shown in a closed position, showing my new design;

FIG. 2 is a rear view thereof;

FIG. 3 is a front view thereof showing the flap in a fully opened position;

FIG. 4 is a left side view thereof showing the flap in the closed position;

FIG. 5 is a rear view thereof showing the flap in the fully opened position;

FIG. 6 is a right side view thereof showing the flap in a first partially opened position;

FIG. 7 is a right side view thereof showing the flap in a second partially opened position;

FIG. 8 is a front view of test strips and a wick as may be disposed within a test kit;

FIG. 9 is a front view of test strips as may be disposed within a test kit;

FIG. 10 is a rear view thereof;

FIG. 11 is a front view of a wick as may be disposed within a test kit; and,

FIG. 12 is a left side view of a test kit showing the flap in the closed position.
